TUBE CUTTING DEVICE

Louis C. Stringer, Chicago, Ill., assignor to Electronics Supply Corp., a corporation of Delaware

Application May 5, 1937, Serial No. 140,957

10 Claims. (Cl. 33—21)

The present invention relates to what is believed to be a structurally new and improved device for scoring glass tubes in general, the specific concept as herein illustrated and particularly described having to do with an ingenious method and means to facilitate accurate and reliable severance of incandescent bulb portions.

Looking toward the promotion of a better understanding of the nature and type of this novel bench-style manually controlled machine, it seems to be in keeping with good policy to direct attention to the specific line of endeavor in which it is particularly adapted for expedient use. To this end it is to be pointed out that certain methods of reclaiming electric lamps and bulbs have been brought into vogue to renovate, repair, and adequately recondition so-called burnt-out lamps.

Persons skilled in the art to which the invention relates are familiar with the fact that when the filament of an incandescent lamp is broken or otherwise impaired, or the effectiveness of gas is destroyed, the lamp is useless unless the filament is properly reconditioned and replaced, this calling for a complete rebuilding of said lamp.

I have discovered the need for the perfection of a complete and systematic method of rejuvenating and reclaiming incandescent bulbs, and inasmuch as one of the procedural steps involved therein necessitates severance of the neck from the bulbous shell to free the filament-equipped mounting, a machine or tool adequate to accomplish this result properly is in demand. Owing to the fragile nature of incandescent bulbs or envelopes, it has been found that the device needed for the purpose intended must be of a manually regulated and hand controlled type, and thus, the purpose of the present invention is to perfect this phase of the general reclamation method through the instrumentality of a structure aptly designed to do the job well.

The procedural aspects and accompanying features and advantages of the invention will be come more readily evident from the succeeding detailed description and the accompanying illustrative drawings disclosing the preferred embodiment of the invention.

In the drawings:

Figure 1 is a side elevational view of the complete assemblage in readiness to accommodate the bulb for severance or cutting, this being constructed in accordance with the principles of the inventive concept.

Figure 2 is a top plan view of the arrangement depicted in Figure 1.

Figure 3 is an enlarged fragmentary view, partly in section, and partly in elevation, said view being on the plane of the line 3—3 of Figure 2.

Figure 4 is a detail section on the line 4—4 of Figure 3.

Figure 5 is what may be called a front end elevation of the oscillatory cutter head with the cover plate removed.

Figure 6 is a horizontal section on the line 6—6 of Figure 5.

Figure 7 is what may be called an end elevation of the adapter abutment.

Figure 8 is a perspective view of one of the spring pressed cutter or diamond point mounts.

Figure 9 is a cross-section on the line 9—9 of Figure 3.

In the drawings, as shown in Figures 1 and 2, the base or supporting frame 10 comprises a suitable bench-type base plate 11 having standards or uprights 12 provided at their upper ends with bearings to accommodate the oscillatory horizontal shaft or arbor 13. This is longitudinally shiftable in the bearings parallel to the plate 11 and held in predetermined set positions by the set screws 14. On the outer end of the arbor is the adapter abutment or fitting to accommodate the incandescent bulb 15 being repaired. The adapter fixture is denoted conveniently by the numeral 16. It comprises a detachable cup 17 having a cushion 18 fitted therein. The cup is detachably mounted on the arbor in any suitable fashion, as indicated at 19.

In practice several different sizes of adapter fixtures 16 will be utilized to accommodate varying types of conventional glass bulbs, or tubes, as the case may be. Incidentally, it may be mentioned that the bulb 15 embodies the conventional bulbous body or shell 20 having a neck 21 formed with the customary sealed-in tip carrying the filament-equipped mount (not shown).

During the course of repair, it becomes necessary, in accordance with my prescribed method, to sever the neck 21 from the body 20 in order that the mount may be removed for reconditioning and repair. This being a precision job, it is necessary to form the score line 22 at a predetermined point forming the juncture of the neck and shell or body 20. This may be satisfactorily accomplished in the present machine through the instrumentality of the cutter-equipped mandrel unit mounted on the arbor 13.

The aforementioned unit comprises a mandrel proper in the form of a sleeve 23, this being slid-

ably and rotatably mounted on the arbor. The sleeve forms a convenient hand grip and it is provided at a predetermined point with a resilient latch 24 having a V-shaped detent 25 5 releasably engageable with threads 26, whereby to provide a sort of a rack and pawl locking connection between the mandrel and arbor. The use of the annular threads 26 makes it possible to readily slide the mandrel to the desired position on the arbor, lock it, and thereafter freely 10 oscillate it or turn it for the cutting operation. On the end of the sleeve is a cross-head 27 provided with a pair of spaced parallel supporting rods 28 carrying the cutter head 29. The preferred type of head comprises a disk or plate 30 15 having diametrically opposite grooves formed therein, as seen to advantage in Figure 5. The disk is centrally apertured, as at 31, to admit the entrance of the neck of the bulb, and in effect becomes an oscillatory annulus. Mounted in the grooves are spring pressed blocks or mounts 32 having the scoring point 33 preferably diamond-point. The blocks are pressed simultaneously inwardly under the action of the spring 25 33 held in place by retention cleats 34. These spring pressed cutter elements are shielded and held in place by a detachable face or cover plate 35, as illustrated in Figures 3 and 6.

This complete cutter head, as a unit, is removably supported on the outer ends of the rods 28 30 by quick removable set screws 36 of the type seen in Figure 6. Incidentally, to accommodate different types of bulbs, different sized cutter heads must be employed. The cutter heads are standarized to fit on the rods 28. Moreover, each cutter head is the same in construction, and the only difference is in the accommodation aperture at the center to take care of different sized bulb necks.

40 I next call attention to the numerals 37 which designate latches for actuating trips for the spring pressed cutter elements. The outer ends of the latches extend through slots 38 in the disk 39 and engage the blocks 32, as seen in Figure 3. 45 These latches are pivotally mounted, as at 39, on supporting lugs 40, the latches having operating handles 41 located on diametrically opposite sides of the mandrel or sleeve 23. The handles 41 terminate in spaced relation from the spring 50 pawl 25 so as not to interfere with the action thereof.

With this arrangement it is obvious that the position of the cutter head 29 can be regulated and set with relation to the adapter fixture 16. 55 This determines the position of the score line 22 on the neck of the bulb, as is obvious. In precision work of this character, a fine adjustment is required.

In practice, the position of the cutter head 60 is set or regulated by the means 25 and 26. This is accomplished by bodily sliding the mandrel and its cutter head as a unit on the arbor 13. When the machine is set, the bulb 20 is held in one hand and the neck is inserted through the 65 cutting aperture in the head, the neck being brought to bear against the cushioning block 18 in the adapter cup 17. This is brought out in Figure 3. By holding the bulb in the left hand, for instance, and catching hold of the sleeve 23 70 with the right hand, an oscillatory twist back and forth, generally once around, will score the bulb, after which it can be bodily removed, allowing the neck 21 to be detached to permit access to be had for withdrawing the mount (not 75 shown).

The methodical phase of the inventive concept resides, it is believed, in a method consisting in holding the bulb in one hand, and fitting it into a hand rotated cutting tool, whereby upon holding the bulb stationary and oscillating or turning the tool, the neck may be properly scored and thereafter severed from the body in a prescribed and safe manner. The chief novelty, however, resides, it is believed, in the particular construction of the machine or device for accomplishing this job. 10

It is thought that the description taken in connection with the drawings will enable a clear understanding of the invention to be had. Therefore, a more lengthy description is thought unnecessary. 15

While the preferred embodiment of the invention has been shown and described, it is to be understood that minor changes coming within the field of invention claimed may be resorted to if desired. 20

I claim:

1. A fragile tube cutting device of the class described comprising a support, an arbor on said support, said arbor being provided with an adapter fixture against which one end of a bulb is held, a mandrel mounted for oscillation and sliding on said arbor, said mandrel including an annular cutter head adjustable toward and from said adapter fixture. 25

2. In a device of the class described, a relatively fixed arbor having a cushioned adapted device to accommodate one end of an incandescent or equivalent bulb, a rotary cutter-equipped head adjustable toward and from said fixture and adapted to surround the neck of the bulb, and a mandrel on which said head is mounted, said mandrel in turn being mounted on said arbor. 35

3. A glass cutting device of the class described comprising a relatively stationary arbor having an adapted member on one end, a mandrel rotatably and slidably mounted on said arbor, co-acting means between the mandrel and arbor to limit the sliding movement of the mandrel, a cutter head supported from said mandrel, said cutter head including spring pressed cutter elements, and remote control actuating means for said cutter elements coacting with the cutter elements and mounted on said mandrel. 40

4. In a structure of the class described, an abutment against which one end of a bulb may be held, a cutter head associated with said abutment and adjustable toward and from it, said cutter head being centrally apertured to embrace the neck of the bulb, and manually regulated diametrically opposed spring pressed scoring elements mounted in said head for scoring the neck. 55

5. In a device of the class described, a base including standards, an arbor slidably mounted in said standards, a detachable abutment fixture on said arbor, said arbor being provided with retention elements, a sleeve slidably and rotatably mounted on said arbor and including a pawl cooperable with said retention elements, an annular cutter head, means supporting said cutter head on said sleeve, and latches pivotally mounted on said sleeve and engageable with cutter elements. 60

6. In a structure of the class described, a support including a base having standards rising therefrom, a shaft mounted in said standards, said shaft being provided on one end with a removable cushion-equipped abutment cup, a sleeve mounted on said shaft, coacting means 70

between the sleeve and shaft to permit the sleeve to rotate and to permit it to be slidably adjusted and held in a predetermined adjusted position, and a cutter head fixedly mounted on

5 said sleeve.

7. A glass tube scoring device of the class described comprising relatively fixed adapter and abutment means against which the sealed-in end of a bulb may be braced and held, and 10 complementary scoring means in alignment with and adjustable toward and from said first-named means.

8. A scoring device for glass tube severance of the class described comprising a relatively 15 fixed abutment against which one end of the work is adapted to be held by hand, and a complementary oscillatory scoring unit of a hand rotated type, said scoring unit being located in spaced longitudinal alignment with the abutment

and being adapted to encircle the work to circumscribe a breakable score line around the work at a predetermined distance from said abutment.

9. In a structural assemblage of the class described, a rotary bulb neck embracing and scoring annulus designed to permit the neck of the bulb to be held, by hand, in operative relationship with the scoring means, and a relatively fixed stop in workable alignment with the axis 10 of said annulus to allow one end of the bulb to be pressed thereagainst. 5

10. A bulb scoring device embodying a scoring unit centrally apertured to permit the neck of a bulb to be inserted and projected through 15 and beyond the aperture, and scoring means carried by said unit and cooperable with the aperture to surround said neck.

LOUIS C. STRINGER.
